Specification for Design.

Patented Mar. 15, 1921.

Application filed November 8, 1920. Serial No. 422,740. Term of patent 14 years.

To all whom it may concern:

Be it known that we, GEORGE J. RICHARDSON and WALTER SACHS, citizens of the United States, residing at Petersburg, in the county of Dinwiddie and State of Virginia, have invented a new, original, and ornamental Design for a Combined Trash-Receptacle and Advertising-Carrier, of which the following is a specification, reference being had to the accompanying drawing, forming part thereof, and in which—

Figure 1 is a perspective view of the com-

bined trash receptacle and advertising carrier showing our new design.

Fig. 2 is a plan of the same.

We claim:—

The ornamental design for a combined trash receptacle and advertising carrier, as shown.

GEORGE J. RICHARDSON.
WALTER SACHS.
